UNITED STATES PATENT OFFICE.

JOHN ELLWOOD LEE, OF CONSHOHOCKEN, PENNSYLVANIA, ASSIGNOR TO
THE J. ELLWOOD LEE COMPANY, OF SAME PLACE.

DESIGN FOR A COUPLING FOR ELECTRICAL CONDUCTORS.

SPECIFICATION forming part of Design No. 19,030, dated April 9, 1889.

Application filed March 14, 1889. Serial No. 303,323. Term of patent 14 years.

To all whom it may concern:

Be it known that I, JOHN ELLWOOD LEE, a citizen of the United States, and a resident of Conshohocken, Montgomery county, Pennsylvania, have invented a new and original 5 Design for a Connecting Tip or Coupling for Electrical Conductors, of which the following is a specification.

My design for a connecting tip or coupling 10 for an electrical conductor is fully shown in the side view in the accompanying drawing.

The main body A of the tip is somewhat of the shape of an egg with its end drawn out into or merging into a short rod, a, while the

opposite end, a', is partially drawn out where 15 the insulated cord p passes within it.

I claim as my invention--

The herein-described design for a connecting tip or coupling for an electrical conductor, substantially as shown and described. 20

In testimony whereof I have signed my name to this specification in the presence of two subscribing witnesses.

JOHN ELLWOOD LEE.
